[57] CLAIM

The ornamental design for a combined kitchen brush handle and scraper, as shown and described.

DESCRIPTION

FIG. 1 is a front, top, left perspective view of the combined kitchen brush handle and scraper embodying my new design;

FIG. 2 is a top plan view thereof;

FIG. 3 is a right side elevational view thereof;

FIG. 4 is a left side elevational view thereof;

FIG. 5 is a bottom plan view thereof;

FIG. 6 is a rear elevational view thereof; and,

FIG. 7 is a front elevational view thereof.

The broken line showing of bristles is for illustrative purposes only and forms no part of the claimed design.
